INSERTING MACHINE

Fred W. Barkley, Winthrop, Mass.

Application April 2, 1940, Serial No. 327,429

20 Claims. (Cl. 270—57)

The present invention relates to the manufacture of those ornamental pieces of paper or cardboard, which are sent on certain occasions, such, for instance, as Christmas, Easter, or birthdays, as an expression of compliment or good wishes, and which are herein termed, greeting cards.

Many of these greeting cards comprise a sheet folded twice to form a booklet, known as an 8 page fold, having four leaves and eight pages, the frontispiece often being ornamented by an internal cut-out or border trimming, in which case it is desirable to insert a sheet or foil between the first and second leaves to form a backing of contrasting color for the cut-out, trimmed border, or both of them. Sometimes, the insert sheet is provided with a cut-out somewhat smaller than the cut-out in the frontispiece, so that, when inserted between the first and second leaves, it may be exposed to view along the internal window of the cut-out in the frontispiece and thus decorate it. It is highly desirable that the inserts or backing sheets be inserted in the greeting cards, respectively, in a definite manner, so that the margin of the insert which is exposed to view shall project uniformly beyond the edge of the greeting card the insert is designed to decorate. This desideratum is impracticable commercially, as the inserting operation is a manual operation and thus subject to variations inherent therein.

Furthermore, it is highly desirable that the envelopes in which greeting cards are mailed be associated with the cards when offered for sale. To this end, the manufacturers either insert an envelope between adjacent leaves of the card or insert a card underneath the flap of the envelope. These last two operations, termed "interleaving" and "flapping," respectively, are, like the operation of "inserting" hereinbefore referred to, manual operations. For convenience in disclosure herein, the term "inserting" is used to designate all three of these operations, and any other in which one part is inserted between adjacent faces formed by a fold in another part.

The principal object of the present invention is to produce an inserting machine primarily, but not necessarily, for use in the manufacture of greeting cards.

To the accomplishment of this object, and such others as may appear hereinafter, the various features of the present invention relate to certain constructions, combinations and arrangements of parts hereinafter described and then set forth broadly and in detail in the appended claims 55

which possess advantages readily apparent to those skilled in the art.

The various features of the present invention will be readily understood from an inspection of 5 the accompanying drawings illustrating the best forms of the invention, at present devised, in which,

Figure 1 is a view in plan of the inserting machine, the figure being broken centrally to allow 10 the view to occupy a sheet of the drawings without unduly reducing the size of the illustrated parts, the front of the machine being at the right;

Fig. 2 is a detail view in front elevation, partly 15 in section;

Figure 3 is a detail view in left-side elevation, partly in section;

Fig. 3a is a detail view in sectional elevation on the line 4—4, Fig. 3;

Fig. 4 is a detail view in left-side sectional elevation on the line 4—4, Fig. 1;

Fig. 5 is a diagrammatic view in plan, partly in section, principally of the seven vertical cam-operated rock-shafts and the linkage rocked thereby, the two slides for the two sliding suction cups being shown in construction lines;

Fig. 6 is a detail view in front sectional elevation on the line 6—6, Fig. 1;

Fig. 7, (collectively), is a diagrammatic view 30 in plan showing, generally, right to left, the magazines for supporting in upended stacks the inserts, the greeting cards and the assembled greeting cards and inserts, together with the suction plate, the suction cups, the gripping fingers, the carrier travelling therewith, and the stacker, this figure being used in describing the invention in general terms;

Fig. 8 is a detail view in left-side elevation of 40 the plate which transfers the inserts, one at a time, from the right-hand stack, (Fig. 7), to a position with the greeting card;

Fig. 9 is a sectional view on the line 9—9, Fig. 8;

Fig. 10 is a detail view in longitudinal sectional elevation on the line 10—10, Fig. 1;

Fig. 11 is an enlarged detail view of the discharge face of the nozzle;

Fig. 12 is a detail view in plan of the cam-shaft 50 and the spring constructions which hold some of the cam-rolls engaged with the cams on the cam-shaft;

Fig. 13 is a detail view in sectional elevation on the line 13—13, Fig. 6;

Fig. 14 is a detail view, partly in section, of a

modified form of adjustment for the insert magazine;

Fig. 15 is a detail view in sectional elevation on the line 15—15, Fig. 14;

Fig. 16 is a detail view in sectional elevation of the air valve, and

Fig. 17 is a detail view in left-side elevation, partly in section, of the gripper fingers support.

Described in general terms, the machine is provided with three magazines 20, 21 and 22, (Fig. 7). When the machine is performing the operation in which the inserts are inserted between adjacent leaves of a greeting card, the magazine 20 is provided with an upended stack of inserts 23, each comprising a single sheet, the ornamental face of which is directed toward the discharge end of the magazine. In this operation, the magazine 21 is provided with an upended stack of the greeting cards 24. Each of the greeting cards is provided with a horizontal and a vertical folded edge engaged, respectively, with the bottom and left-hand side of the magazine, viewing the central figure in Fig. 7. Associated with the magazine 21 are three suction cups 25, 26 and 27, the cups 25 and 26 being usually mounted and operated to separate the first or frontispiece leaf of the greeting card from the second leaf thereof, while the second leaf is engaged by the suction cup 27 which holds the second, third and fourth leaves of the card in place upon the right side of the outermost face of the greeting card stack, (Fig. 7). In the meantime, a suction plate 28 is moved first into engagement with the exposed face of the outermost insert in the upended stack in the magazine 20 and then back into the position shown at the right, Fig. 7. The suction plate 28 is then moved to the left, (Fig. 7), to bring the plate and the insert carried thereby within the first and second leaves of the card while they are held separated by the suction cups 25, 26 and 27.

During this movement of the suction plate 28, a tray 29 and a pair of gripping fingers 30 travelling therewith are moved from the full-line position of Fig. 7 to the construction-line position thereof to insert the tray 29 under the horizontal folded edge of the greeting card, (shown in the central position of Fig. 7), and to cause the gripping jaws 30 to grasp the vertical folded edge 31 thereof and the vertical fold separating the third and fourth leaves of the card and bind the adjacent faces of the first and second leaves of the card upon the included insert. The suction on the cups 25 and 26 and the plate 28 is then broken to allow the tray 29 and the gripping jaws 30 to pull the card, together with the insert, away from the suction cup 27 until the vertical folded edge 31 of the card engages an extension 32 on the left-hand side of the magazine 22, viewing Fig. 7, at which time, the jaws 30 are opened to release the assembled card and insert, so that a stacker 33 may push them into the open-end of the magazine 22. In addition to these fundamental operating instrumentalities, described in general terms, the machine is provided with a nozzle which applies a spot of adhesive in each cycle of operations to the exposed face of the outermost insert in the stack in the magazine 20, in order that the insert may become secured adhesively to the card under the pressure exerted upon it in the magazine 22.

As indicated in Fig. 7, the outermost insert stacked in the magazine 20 is located in an oblique vertical plane corresponding, generally, to the oblique vertical plane in which the second

leaf of the greeting card lies when the first and second leaves are held separated from each other and from the stack of cards in the magazine 21, by the suction cups 25, 26 and 27. The three magazines are adjustable in the direction of their lengths and also for different widths of cards and inserts. In addition, the magazine 20 is provided with adjustments, whereby it can be held elevated above the magazine 21, so that the insert can be inserted in the greeting card at varying distances from the bottom fold thereof, whereby it can be shifted bodily toward and away from the magazine 21, and whereby the front portion thereof can be tipped laterally to predetermine the correlated relationship between the adjacent edges of the greeting card and the insert when inserted therewithin.

As the suction cups 25, 26 and 27 hold the first and second leaves of the greeting card gaped vertically from the bottom fold and laterally from the vertical fold, (Fig. 7), the suction plate 28, instead of travelling in a straight path to insert the insert between the separated first and second leaves of the greeting card, is first elevated in a vertical plane to a height above the greeting card and then depressed sharply in the same vertical plane, so that the plate 28 may enter between the separated first and second leaves of the card in a direction downwardly towards the bottom fold of the card and rearwardly towards the vertical fold thereof, thus to take advantage of the wider gaping portion between the first and second leaves.

When the interleaving operation is performed in the machine, the envelopes are stacked in the magazine 20, are withdrawn, one at a time, therefrom, and are inserted in the greeting cards, which are withdrawn, one at a time, from the magazine 21, the machine operating exactly as in the inserting operation previously described in general terms, except that the adhesive spotting mechanism is suspended, the suction plate is moved rearwardly, after it engages the envelope, to pull the leading edge thereof out from under the left-hand magazine retaining clip shown in Fig. 7, and the position of the greeting cards in the stack thereof may be reversed.

When the flapping operation is performed, the greeting cards and envelopes are withdrawn, one at a time, respectively, from the magazines 20 and 21, respectively, the adhesive spotting mechanism being suspended and the suction plate 28 having an additional movement imparted to it, in order to pull the leading edge, corresponding to the leading edge 35 of the insert shown in Fig. 7, out from under the left-hand magazine retaining clip shown therein. The other operations to complete the flapping operation are the same as previously described for the inserting and interleaving operations.

Referring now to Figs. 1 and 6, the magazine 20 comprises a horizontal bottom board 36, which is supported by two cross-pieces 37 and 38 unsupported at the left, (Fig. 1), but terminating at the right in bosses 39 and 40, respectively, which are perforated to receive vertical rods 41 and 42 rising from the top surface of a table 43. The bosses 39 and 40 are provided with set-screws 44 and 45, (Figs. 1 and 2), so that the magazine 20 may be held on the rods 41 and 42 at varying heights above the table 43 in order to vary the location of the inserts 23 within the cards 24 relative to the folded edges thereof by which they are supported upended in a stack in the magazine 21.

The inserts 20 are retained in position on the board 36 by a pair of angular sheet metal pieces, each comprising a vertical plate 46 and a flange 47 inturned therefrom towards the central board 36 to cooperate therewith in supporting the bottom of the insert stack. The flanges 47 are countersunk to receive the flanged heads 48 of fastenings, the threaded shanks of which enter slots 49 and 50, respectively, in the cross-pieces 37 and 38, butterfly nuts, (not shown), on the free ends of the shanks of the fastenings serving to clamp the two vertical sides 46 in any desired position of adjustment towards and from each other.

As shown in Fig. 1, the left-hand vertical side 46 is longer than the other vertical side, so that the face of the outermost insert in the stack extends in an oblique vertical plane, the leading edge 35 of the outermost insert being slightly in advance laterally of the trailing edge thereof with respect to the open-end of the magazine 20. The leading and trailing edges of the outermost insert in the stack are engaged, respectively, by clips 51 and 52 carried, respectively, by the front ends of the vertical sides 46.

In order to press the exposed face of the outermost insert in the stack against the clips 51 and 52, the rear face of the stack is engaged by a board 53, (Fig. 6), engaged in turn by a sheet metal follower 54. Depending from the bottom of the follower 54, (Fig. 13), are two blocks 55 and 56 which embrace the opposite sides of the board 36, two straps 57 and 58 secured to the bottoms of the blocks 55 and 56 acting as ways to permit the follower 54 to slide on the board 36 as the stack of inserts diminishes in size. The follower 54 is maintained pressed against the board 53 by a weight 59, (Fig. 2), on the free-end of a cord 60, the other end of which is secured to the bottom of the strap 57, (Fig. 13). Intermediate its length, the cord 60 passes around a horizontally arranged pulley 61, (Figs. 1 and 6), carried by the front end of the board 36 and around a vertically arranged pulley 62 journaled in brackets 63 depending from the rear-end of the board 36.

With this construction, the vertical sides 46 of the insert magazine 20 may be adjusted to accommodate it to different widths of inserts and the magazine 20 may be adjusted in the direction of its length and also elevated on the vertical posts 41 and 42 to vary the position of the lower edge of the insert relatively to the bottom fold of the card in which the insert is to be inserted.

As a further adjustment, the magazine 20 may be adjusted bodily laterally and the front portions of the walls 46, viewing Fig. 1, may be tilted laterally of their lengths to predetermine accurately the correlated relationship of the bottom of the insert and the bottom of the card in which the insert is to be inserted.

To this end, the hub 40, (Figs. 14 and 15), of the cross-board 38, besides being mounted loosely on the vertical rod 42, may be embraced by the jaws 64 and 65. On one side of the rod 42, the hub 40 and the jaws 64 and 65 are pivoted on a horizontal pin 66. On the opposite side of the rod 42, the hub 40 and the jaws 64 and 65 carry a headed bolt 67, the shank of which passes through a curved slot 68 formed in the hub 40 and the jaws 64 and 65, the threaded end of the bolt 67 carrying a butterfly nut 69 to take up the limited movement of the parts around the pivot pin 66.

The bottom of the rod 42 is reduced in size,

(Fig. 15), and is secured to a pedestal block 70 which slides in ways formed in a slideway 71 secured to the table top 43. To slide the pedestal block 70 and thus adjust the magazine 20 bodily towards and from the front of the machine or to and from the magazine 21, the block 70 is tapped to receive one end of a threaded rod 72 which is mounted to rotate, but held from longitudinal movement in, a bracket 73 on the table top 43, the free end of the rod 72 having a manipulating handle 74.

The table top 43, (Fig. 1), also supports two crosspieces 75 and 76 which carry the magazine 21 for the greeting cards and the magazine 22 in which the assembled cards and inserts are stacked, the magazine 21 comprising a pair of angular plates 77 and 78, constituting the sides and bottom of the magazine 21, the plates being adjustable towards and from each other and in the direction of their lengths, as in the magazine 20. The magazine 22 comprises a pair of angular plates 79 and 80, constituting the sides and bottom of the magazine, the plates being adjustable towards and from each other and in the direction of their lengths, as in the magazines 20 and 21.

The stack of greeting cards 24 is inserted in the magazine 21, so that one fold on each of the cards rests upon the inturned flanges of the magazine and so that the other fold on each of the cards engages the left-hand vertical wall of the magazine, viewing Fig. 7, thus leaving free edges of the card at the top and at the side, directed towards the leading edge 35 of the insert carried by the suction plate 28.

The outermost greeting card in the stack in the magazine engages a stationary clip 81, (Fig. 3), secured to the wall 78 of the magazine 21 and a disk 82 secured to the front end of a horizontal rod 83, (Fig. 4), which is mounted to slide in supports 84 and 85 secured to the exterior of the wall 77 of the magazine 21. The disk 82 is held pressed against the outermost face of the stack of greeting cards 24 in the magazine 21 by a spring 86 coiled about the rod 83 and interposed between the support 84 and a collar 87 adjustably carried by the rod 83. The spring 86 holds the disk 82 in engagement with the outermost face of the stack of greeting cards in the magazine 21 under a light, critical pressure, so that it offers but little resistance to the withdrawal of the outermost greeting card in the stack by the suction cups 25 and 26, (Fig. 7). Preferably, the extent of movement which the disk 82 is permitted to make either in or out of engagement with the outermost face of the greeting card in the stack is limited by a stop 88 which is mounted on the rod 83 to engage the support 85.

In order to maintain the outermost face of the stack of greeting cards 24 pressed against the clip 81 and the disk 82, notwithstanding successive withdrawals of the outermost greeting card in the stack, the stack is fed towards the exit of the magazine 21 by rubber or friction tapes which engage the bottom folds on the cards in the stack, the back face of which is engaged by the vertical face of a book-end 89, which aids somewhat in the feeding of the stack, but the principal function of which is to prevent the cards in the stack from falling backwardly.

The horizontal face of the book-end 89 rests upon the upper runs of a pair of rubber or friction-surfaced tapes 90 and 91, (Figs. 1 and 4).

The tape 90 near the front of the magazine 21 passes around a pulley 92, (Figs. 1 and 4),

mounted upon a horizontal shaft 93 supported upon brackets 94 secured to the table top 43. The rear end of the tape 90 passes over a pulley 95 secured to a horizontal shaft 96 journalled in bearings 97 and 98 on brackets 99 and 100 secured to a flange 101 depending from the table 43. The lower runs of the tapes 91 and 92 pass over a roll 102 rotatably mounted in brackets 103 and 104 carried by the table top 43.

The upper run of the tape 91 passes over a pulley 105, (Fig. 1), on the shaft 93 and a pulley 106 on the shaft 96. As indicated in Figs. 1 and 4, the pulley 106 is larger than the pulley 95, so that the tape 91 will feed the free or thinner edges of the greeting cards 24 stacked in the magazine 21 faster than the folded or thicker edges.

To drive the shaft 96, it carries a ratchet 107, (Fig. 4), which is driven in a step-by-step manner by a spring-pressed-driving pawl 108 pivoted upon a plate 109 integral with a depending arm 110, both the plate and the arm being loosely mounted upon the shaft 96 between the ratchet 107 and a collar 111, (Fig. 1), secured to the shaft 96.

The plate 109 carries a weight 112, (Fig. 4), which normally rotates the plate and the arm 110 counterclockwise, (Fig. 4), to hold the shank of a bolt 113, which connects the free end of the arm 110 to one end of a link 114, in engagement with the bottom of a slot 115 therein. The other end of the link 114 is pivotally connected to an arm 116, (Fig. 5), projecting from a vertical rock-shaft 117, the opposite ends of which oscillate in pedestal boxes 118 and 119, (Fig. 4), secured, respectively, to the bottom of the table 43 and a platform 120 secured to webs 121 and 122, which connect the front pair of legs 123 to the back pair of legs 124, upon which legs the table 43 is supported.

Projecting laterally from the rock-shaft 117 is an arm 125, (Fig. 12), upon the free end of which a roll 126 is mounted in position to engage the face of a cam 127 mounted upon a cam-shaft 128. The roll 126 is maintained engaged with the cam 127 by a spring 129 which is coiled around a rod 130 one end of which passes loosely through a bracket 131 on the platform 120. The spring 129 is interposed between the bracket 131 and a head 132 on the rod 130. A conical depression on the head 132 is engaged by a conical point 133 carried by one end of an arm 134 projecting from the rock-shaft 117.

The cam-shaft 128, (Fig. 2), is provided with a worm-wheel 135 which is mounted within a commercial form of worm-gear-speed-reducer 136 secured to the platform 120. The worm-wheel 135 is driven by a worm 137, (Fig. 2), mounted on a horizontal shaft 138 journalled in brackets 139 depending from the bottom of the table 43. The shaft 138 is provided with a pulley 140 which is driven by a belt 141 from a pulley 142 mounted on a jack-shaft 143 carried by a standard 144 secured to a platform 145 joining the webs 121 and 122. The jack-shaft 143 is driven from the electric motor 147 by a belt 148 which passes around a pulley 149 on the commutator shaft 150 and a pulley 151 on the jack-shaft.

With this construction, the link 114, (Fig. 4), is vibrated to oscillate the plate 109 and the depending arm 110 on the shaft 96, thus to impart a succession of driving steps to the ratchet 107 to drive the tapes 90 and 91 and maintain the outermost greeting card in the magazine pressed

against the stationary clip 81 and the movable disk 82, a spring-pressed pawl 152, (Fig. 4), pivoted on the bottom of the bearing 97, (Fig. 1), serving to hold the ratchet 107 in the angular position to which it has been rotated by the pawl 108.

As the movable disk 82 is held against the outermost card in the stack of greeting cards in the magazine with a light, critical pressure, it is desirable to provide mechanism for interrupting the feed of the greeting cards forwardly in the magazine 21 as soon as a tendency develops for the stack of greeting cards to push the disk 82 outwardly against the pressure of the spring 86, (Fig. 4). To this end, the rear end of the rod 83 is connected to one end of a small lever 152 centrally pivoted on a bracket 153 carried by the flange 101. The lower end of the lever 152 is shaped as a latch 154.

When the disk 82, (Fig. 4), is in a normal position, the spring 86 holds the latch 154 out of engagement with a ledge 155 on the feeding plate 109. When the pressure exerted by the stack of greeting cards being fed forwardly in the magazine 21 moves the disk 82 outwardly, or to the right, viewing Fig. 4, the rear end of the rod 83 allows the latch 154 to engage over the ledge 155, thus preventing the return of the plate 109 and arm 110 to their original positions under the influence of gravity and thus preventing further oscillation of the plate 109 and the arm 110 on the shaft 96, the shank of the bolt 113 vibrating idly in the slot 115. The continued feed of the stack of greeting cards in the magazine 21 is suspended until the release of the pressure on the disk 82 enables the spring 86 to withdraw the latch 154 from the ledge 155, thus to permit the plate 109 to resume its feed of the ratchet 107.

The storage magazine 22 for the cards, which have been provided with inserts, is similar to the other two magazines, except that it is longer and differs in the character of the clips which engage the outermost face of the cards in the stack. As shown in Fig. 1, the exterior of the walls 79 and 80 of the magazine 22 are provided, respectively, with a spring-pressed clip 156, the free end of which is bent around the vertical end face of such walls into engagement with the outermost face of the card in the stack. The wall 79 of the magazine 22 is extended, (Figs. 1 and 4), to act as the stop 32, (Fig. 7), hereinbefore referred to.

In order to withdraw the inserts 23 from the insert magazine 20, the machine is provided with a suction plate 28, (Figs. 1, 3, 8 and 9), which is provided with a short vertical portion 157 and a longer horizontal portion 158. These portions are provided with a connected internal passage 159, the vertical portion thereof having three short passages 160 connecting the passage 159 to the atmosphere, and the horizontal portion of the passage having a short passage 161 connecting the passage 159 through a flexible tube 162 connected to a suitable air-exhausting system, (not shown), for causing atmospheric air to be drawn into the suction plate and out through the tube 162 in the direction of the arrow, (Fig. 1). Adjacent each of the openings 160, the face of the suction plate 28 is countersunk to provide a seat 163 for a rubber-ring washer 164.

One end of the horizontal portion of the suction plate 28 is connected to a block 165, (Figs. 1, 2 and 3), which is clamped to one end of a vertical rod 166 rising from a yoke 167 pivoted on a horizontal pin 168 carried by a slide 169 mounted

to slide in a horizontal plane parallel to the horizontal axis about which the yoke 167 tips.

The slide 169, (Figs. 2 and 5), is mounted to slide in ways 170 formed in a carriage 171 mounted to slide on a horizontal rod 172. The carriage 171 is provided with ears 173 which embrace a stationary ledge 174 supported from the bottom of the table 43. The slide 169 carries a roll 175 which is held pressed against an elongated bar 176 by a coiled spring 177 interposed between the carriage 171 and a block 178 on the slide 169.

The opposite ends of the bar 176 are pivotally connected to two arms 179 and 180 carried, respectively, by two vertical rock-shafts 181 and 182 pedestaled like the rock-shaft 117, (Fig. 4). Projecting from the rock-shaft 181 are two other arms 183 and 184, (Fig. 12). The outer end of the arm 183 carries a roll 185 on the cam-shaft 128, the roll being held engaged with the cam 186 by a spring 187 having a construction and mode of operation like the spring 129.

The suction plate carriage 171 is slid along the rod 172 and the ledge 174 from a face cam 188, (Figs. 4 and 12), on the cam-shaft 128, through engagement with a roll 189 mounted on the longer arm of a lever 190 pivoted on a short rod 191 projecting inwardly from the platform 120. The roll 189 is held in engagement with the face cam 188 by a spring 192, (Fig. 3), which is coiled about a rod 193 mounted to slide and oscillate in an opening 194 formed in a bracket 195 secured to the platform 196. The rod 193 is provided with a head 197 between which and the bracket 195 the spring 192 is interposed. The exterior 35 of the head 197 is provided with a conical depression which receives a conical point 198 on the shorter arm of the lever 190.

The longer arm of the lever 190 is connected to one end of a link 199, the other end of which is provided with a lateral pin 200 which is received in a slot 201 formed in an arm 202. The lateral pin 200 may be held in the slot 201 in any desired position of adjustment by two screws 203 and 204 carried by the arm 202. The arm 202 swings on a stub-shaft 205 secured to a bracket 206, (Fig. 4), projecting inwardly from the web 122. The upper end of the arm 202 is provided with a slot 207 which receives adjustably a pin 208 carried from the bottom of the carriage 169.

With this construction, the cam 127, through the slide 169, first moves the suction plate 28 into engagement with the outermost insert in the magazine at a time when the plate, as will be described hereinafter, is under a condition of unbalanced atmospheric pressure, to enable the plate to pick the outermost insert in the magazine 20 from the stack therein, and then withdraw the plate, with the insert retained thereon, into the path along which the plate is reciprocated by the cam 188 to bring both the plate and the insert into the critical position of Fig. 7 and to return the plate to its original position preparatory to a new cycle of operations. During the movement of the suction plate by the cam 188, the cam 127 functions to maintain the bar 176, (Fig. 5), in proper position to allow the roll 175 to run therewithout actuation of the slide 169.

In the inserting operation, the suction plate moves in a constant path into and out of engagement with the outermost insert stacked in the magazine 20, as the insert is sufficiently flexible to be pulled from under the clips 51 and 52. In the interleaving and flapping operations, however, the envelopes and the greeting cards are stacked, re-

spectively, in the magazine 20, so that it is desirable to impart to the suction plate 28 an additional movement towards the front of the machine after the suction plate has engaged with the outermost envelope or greeting card in the stack, as the case may be, in order that the leading margin of the envelope or greeting card may buckle slightly and thus slip out from under the clip 51, the suction plate then having a compound movement, under the influence of both of the cams 127 and 186, outwardly away from the stack of envelopes or greeting cards and forwardly into the path in which the suction plate travels to place the envelope or greeting card carried thereby in between the greeting card or the flaps of the envelope, as the case may be, held separated by the suction cups 25, 26 and 27 at the central station, Fig. 7.

This desirable additional movement imparted to the suction plate 28 in connection with the picking up of envelopes or greeting cards and the removing of them, one at a time, from the magazine 20, is obtained merely by an angular adjustment of the cam 186 on the cam-shaft 128. 20 To this end, the hub 209, (Fig. 12), of the cam 186 is provided with a slot 210 which embraces the shank of a screw 211 by which the hub 209 is secured to the cam-shaft 128. Actually, the cam 186 is shifted angularly to operate its connections to the suction plate 128 earlier in flapping and interleaving than in inserting.

Referring now to the central figure in Fig. 7, it is clear that, as the first and second leaves of the greeting card are held separated by the suction cups 25, 26 and 27, waiting the arrival of the suction plate 28 with the removed insert thereon, the separation between the first and second leaves diminishes in width from the tops thereof downwardly to the common fold therebetween, and that, therefore, the higher up, relative to the bottom fold, the insert enters between the separated first and second leaves, the less chance there is for an improper insertion.

In order that the suction plate 28 may insert the insert between the separated first and second leaves of the greeting card in a path which is downward and rearward, relatively to the bottom and vertical folds of the greeting card, the yoke 167 carries a cylindrical roll 211a which engages a cam path 212 in a stationary plate 213 which is adjustable vertically on the vertical arms 214 of brackets 215 adjustably mounted on the table 43. The cam path 212 is shaped to tip the suction plate 28 upwardly about the pivot 55 168 and thus elevate the plate above the plane of the tops of the first and second leaves of the greeting card and then, as the insert starts to enter between the first and second leaves of the greeting card, to tip the suction plate downwardly to cause the insert to move downwardly and rearwardly into proper relationship with the bottom and vertical folds common to the separated first and second leaves of the greeting card.

65 The adjustable connection for the cam plate 213 permits it to be tipped upwardly or downwardly in a vertical plane to correlate its angular position with the angular position of the magazine 20, when the latter is adjusted through manipulation of the hand-wheel 74, (Fig. 14).

In order to provide the outermost insert in the magazine 20 with a spot of adhesive before it is withdrawn from the stack therein, the machine is provided with a source of adhesive supply comprising a tank 216, (Fig. 2), carried high above

the table 43 on a rod 217 secured thereto. One end of a flexible tube 218 is connected to the bottom of the tank 216, so that the adhesive may flow from the tank into the flexible tube under the influence of gravity. The other end of the flexible tube 218 is connected to a nozzle 219 having a frusto-conical discharge passage 220, (Fig. 10), maintained normally closed by a blunt frusto-conical needle 221 backed by a coiled spring.

The nozzle 219 is clamped to a block 222, (Figs. 2 and 6), which is connected adjustably to an arm 223 secured to a vertical rock-shaft 224, (Figs. 1, 4 and 5), journalled in the table 43. The rock-shaft 224 is provided with a second arm 225, (Fig. 12), having a cam roll 226 held engaged with the face of a cam 227 on the cam-shaft 128 by a spring construction, the details of which are similar to the corresponding constructions associated with the cams 127, 186 and 203.

As indicated in Fig. 11, the front face of the nozzle 219 which contains the discharge orifice is roughened, so that, when the cam 227 forces the nozzle into engagement with the outermost insert stacked in the magazine 20, the portion of the insert to be spotted with adhesive is roughened to provide a good holding surface for the adhesive which flows out of the nozzle through the discharge orifice when the needle 221 recedes within the nozzle upon contact with the stack of inserts.

As pointed out heretofore, the operation of the nozzle is suspended when the machine performs the operations of interleaving and flapping. To this end, the rod 217 carries a collar 228 which in turn carries a hook 229 arranged to latch the nozzle-carrying arm 223 in an inoperative position, in which position the cam roll 226, (Fig. 12), is drawn away from the cam 227.

Referring back to the central figure, Fig. 7, the suction cups 25, 26 and 27 are shown holding the first and second leaves of the greeting card separated, with the insert and the suction plate positioned within the separated first and second leaves.

The suction cup 27, (Figs. 1 and 3), is carried, laterally adjustable, upon a flat plate 230 which is adjustable vertically on a vertical rod 231 supported from the wall 78 of the magazine 21. The suction cup 27 is connected by a flexible hose 232 to the air-exhausting system, (not shown).

The suction cups 25 and 26 are connected, respectively, to flexible hoses 233 and 234, (Fig. 1), which are connected together and to the flexible hose 162 through a pipe 235, (Fig. 16), which is connected through a rotary valve 236, to be described, to a pipe 237 which conducts the air drawn through the suction plate, and the suction cups 25 and 26 to the air-exhausting system, (not shown).

The suction cup 26 constitutes the air-receiving end of a tube 238 to which the flexible hose 234 is connected. The tube 238 is carried by a sleeve 239 which is connected adjustably, within an inclined slot 240, to an arm 241 which is pivoted on a horizontal axis to a sliding link 242 mounted to slide in ways 245 carried by the table 43. One end of the sliding link 242 is pivoted to the free end of an arm 246 projecting laterally from a vertical rock-shaft 247 pedestaled like the rock-shafts 117 and 181.

The rock-shaft 247 is provided with an arm 248 which is connected through a link 249 to an arm 250 projecting from a vertical rock-shaft 251

pedestaled like the rock-shafts 117, 181 and 247. The rock-shaft 251, (Fig. 12), is provided with an arm 252 having a roll 253 therein which is held engaged with a face cam 254 on the cam-shaft 128 by a spring construction similar to the ones that maintain the rolls 126 and 185 engaged, respectively, with the cams 127 and 186.

The suction cup 25 constitutes the air-receiving end of a tube 255 to which the flexible hose 233 is connected. The tube 255 is carried by a sleeve 256 which is connected adjustably, within a vertical slot 257, to an arm 258 adjustable laterally upon a link 259 and provided with an open-ended slot 260 which receives a pin 261 to control the sliding movement of the link.

With this construction, the slides 242 and 259, carrying the suction cups 26 and 25, respectively, are connected, (Fig. 5), to the arm 246 different distances from the axis of the rock-shaft 247 in order to permit the suction cup 26 to move a greater distance than the suction cup 25 in separating the outermost first leave of the greeting card from the leave held by the suction cup 27, (Fig. 7).

With the construction and mode of operation so far described, the insert has been inserted within the separated leaves of the greeting card, as indicated in the central view of Fig. 7. In order to break the suction on the suction cups 25 and 26 and the suction plate 28, and thus permit them to release the card and its insert for the operation of the tray 29 and the gripping fingers 30 at the proper time, the valve 236, (Fig. 10), is carried by an arm 262, (Fig. 5), projecting laterally from the rock-shaft 117. The upper face of the valve 236 is held pressed against the lower face of a wooden block 263, (Fig. 16), by a spring 264 which is coiled about a stem 265, on the block 263, loosely mounted in an opening 266 in the table 43, and interposed between the bottom of the table and the top of the block.

The valve 236 is provided with an opening 267 to which the pipe 235 is connected. When the suction is on, the opening 267 registers with the inlet of a passage 268, in the block 263, to the outlet of which the pipe 237 is connected. When the cam 127 oscillates the valve 236 from the full to the construction-line position of Fig. 16, a port 267a, open to the atmosphere, registers with the passage 268 and the suction is broken.

The tray 29, (Figs. 1, 3 and 7), comprises a horizontal piece of sheet metal, (Figs. 1 and 3), secured to the top of a bracket 268a, the bottom of which is secured to a carriage 269 mounted to slide on the rod 172 and ledge 174 like the carriage 169. The carriage 269 is reciprocated from a cam 270 on the cam-shaft 128 by mechanism duplicating that which reciprocates the carriage 169 from the cam 188.

The gripping fingers 30 are also supported from the carriage 269. To this end, the carriage is provided with a block 271, (Figs. 4 and 17), which receives, in spaced relation, the vertical spindles 272 and 273 from which the fingers are supported, respectively. The spindles 272 and 273 carry small gears 274 and 275, respectively, which are meshed in order that the gripping fingers may open and close in unison. The extent of movement of the fingers 30 from an open to a closed position is controlled by the engaged slabbed-off faces of two semi-cylindrical bosses 276 and 277, (Fig. 1), formed on the spindles 272 and 273, respectively.

In order to open and close the fingers and to hold them in their open and closed positions, the

spindle 273 of one of the fingers 30 is extended below the bottom of the block 271 and is provided with a laterally extended arm 278 having the spaced dimples 279 and 280, (Fig. 5). When the carriage 269 is in its normal position, the arm 278 is engaged by a vertical rod 281, (Fig. 5), which causes the fingers 30 to open, a spring-pressed ball 282, (Figs. 4 and 17), carried by the block 271 engages the dimple 279 to hold the fingers normally open. When the carriage 269 is reciprocated to position the fingers 30 upon opposite sides of the folded edge 31 and the folded edge separating the third and fourth leaves of the greeting card, (Fig. 7), the arm 278 engages a vertical rod 283, (Fig. 5), to close the fingers on the two vertical folded edges and to bind the insert between the internal adjacent faces of the vertical folded edge 35, the ball 282 then dropping into the dimple 280 to hold the fingers 30 closed during the return of the carriage 269 to its initial position, at which point the arm 278 engages the rod 281 to open the fingers and to return the ball into engagement with the dimple 279.

The stacker 33, (Fig. 7), comprises two vertical plates 284 and 285, (Figs. 1 and 3), each of which is connected centrally to a plate 286, which are engaged, back to back, they being secured together in a longitudinally adjustable manner, by a clamp 287 carried by one end of a horizontal rod 288 which is connected by an arm 289 to the clampable free end of a vertical arm 290. The vertical arm 290 projects from a hub 291 which is mounted loosely upon a horizontal rod 292 carried by brackets 293 on the table 43.

To reciprocate the stacker into and out of the entrance to the magazine 22, the hub 291 is connected to the free end of a vertical rod 294 which slides in a slot 295 through the table 43. The lower end of the rod 294 is embraced by the free end of a link 296 which is pivoted on a vertical rod 297. The other end of the link is connected to one end of a link 298, the other end of which is connected to an arm 299 projecting laterally from a vertical rock-shaft 300, pedestaled, like the other cam-operated rock-shafts. The rock-shaft 300 is provided with an arm 301 having a cam roll 302 thereon which is held engaged with a cam 303 on the cam-shaft 128 by a spring construction similar to the spring construction associated with the cams 121, 186 and 253.

Nothing herein explained is to be interpreted as limiting the various features of the present invention in the scope of its application to use in connection with the particular machine or the particular mode of operation or any combination thereof selected for purposes of illustration and explanation. While the particulars of construction herein set forth are well suited to one mechanical form of the invention and to the uses to which it is put, it is not limited as to these uses, nor to these details of construction, nor to the conjoint use of all its features, nor is it to be understood that these particulars are essential since they may be modified within the skill of the artisan without departing from the true scope of the actual invention, characterizing features of which are set forth in the following claims by the intentional use of generic terms and expressions inclusive of various modifications.

What is claimed as new is:

1. An inserting machine having, in combination, a source of supply for folded sheets, a source of supply for inserts, means for withdrawing the first and a portion of the second leaves of a folded sheet from the first-named source of sup-

ply, and means for withdrawing an insert from the second-named source of supply and inserting the withdrawn insert within the withdrawn portion of the folded sheet.

5. An inserting machine having, in combination, a source of supply for folded sheets, a source of supply for inserts, said sources of supplies extending parallel to each other, means for withdrawing the first and a portion of the second

10 leaves of a folded sheet from the first-named source of supply, and means for withdrawing an insert from the second-named source of supply and inserting the withdrawn insert within the withdrawn portion of the folded sheet.

15 3. An inserting machine having, in combination, a source of supply for folded sheets, a source of supply for inserts, suction means for withdrawing the first and a portion of the second leaves of a folded sheet from the first-named source of supply, and suction means for withdrawing an insert from the second-named source of supply and inserting itself and the withdrawn insert within the withdrawn portion of the folded sheet.

20 4. An inserting machine having, in combination, a source of supply for folded sheets, a source of supply for inserts, suction means for withdrawing the first and a portion of the second leaves of a folded sheet from the first-named source of supply, and suction means for withdrawing an insert from the second-named source of supply and inserting itself and the withdrawn insert within the withdrawn portion of the folded sheet, and means for breaking the suction on said suction means when the second-named suction means is within the withdrawn portion of the folded sheet.

25 5. An inserting machine having, in combination, a source of supply for folded sheets, a source of supply for inserts, means for withdrawing the first and a portion of the second leaves of a folded sheet from the first-named source of supply, means for withdrawing an insert from the second-named source of supply and inserting the withdrawn insert within the withdrawn portion of the folded sheet, and means engaging the portion of the folded sheet withdrawn from the first-named source of supply for binding the insert within said portion and for completing the removal of the folded sheet from the first-named source of supply.

30 6. An inserting machine having, in combination, three magazines, comprising, respectively, a source of supply for folded sheets, a source of supply for inserts, and a storage supply for folded sheets each having an insert therein, and means for withdrawing the first and a portion of the second leaves of a folded sheet and an insert from the respective source of supplies, inserting the withdrawn insert between the first and a portion of the second leaves connected by a fold of the withdrawn folded sheet, and stacking the assembled folded sheet and insert into the third magazine.

35 7. An inserting machine having, in combination, a source of supply for folded sheets, a source of supply for inserts, means for withdrawing a portion of a folded sheet from the first-named source of supply including the first and a portion of the second leaves connected by a bottom fold and a rearwardly directed vertical fold, and means for withdrawing an insert from the second-named source of supply and inserting the withdrawn insert between said leaves in a direction downwardly and rearwardly relative to the bottom and vertical folds, respectively.

8. An inserting machine having, in combination, a source of supply for folded sheets, a source of supply for inserts, means for withdrawing a portion of a folded sheet from the first-named source of supply including the first and a portion of the second leaves connected by a bottom fold and a rearwardly directed vertical fold, means for correlating the positions of a folded sheet and an insert in their respective magazines, and means for withdrawing an insert from the second-named source of supply and inserting the withdrawn insert within the withdrawn portion of the folded sheet.

9. An inserting machine having, in combination, a source of supply for folded sheets, a source of supply for inserts, means for withdrawing a portion of a folded sheet from the first-named source of supply including the first and a portion of the second leaves connected by a bottom fold and a rearwardly directed vertical fold, means for correlating the positions of a folded sheet and an insert in their respective magazines, means for withdrawing an insert from the second-named source of supply and inserting the withdrawn insert within the withdrawn portion of the folded sheet, and means for correlating the last-named means with the correlated positions of a folded sheet and an insert in their magazines, respectively.

10. An inserting machine having, in combination, a magazine for a stack of folded sheets, the folds making the stack longer along one side face than the other side face, and means for feeding the longer side face of the stack slower than the opposite side face.

11. An inserting machine having, in combination, a magazine for a stack of inserts, and means for roughing a spot on the outermost insert in the stack and depositing adhesive on the roughened spot.

12. In an inserting machine, the combination with a pair of gripping fingers movable forwardly and backwardly in a path, of stationary means for closing the pair upon reaching the end of the path in one direction.

13. In an inserting machine, the combination with a pair of gripping fingers movable forwardly and backwardly in a path, of stationary means for opening the pair upon reaching the end of the path in one direction.

14. In an inserting machine, the combination with a pair of gripping fingers movable forwardly and backwardly in a path, of stationary means for closing the pair upon reaching the end of the path in one direction, and stationary means for opening the pair upon reaching the end of the path in the opposite direction.

15. In an inserting machine, the combination with a pair of gripping fingers movable forwardly and backwardly in a path, stationary means for closing the pair upon reaching the end of the path in one direction, and stationary means for opening the pair upon reaching the end of the path in the opposite direction, of means for holding the pair opened and closed, respectively, during the forward and backward movement thereof.

16. An inserting machine having, in combination, a source of supply for folded sheets, a source of supply for inserts, means for withdrawing the first and a portion of the second leaves of a folded

sheet from the first-named source of supply, means for holding at least a portion of the remaining portion of the folded sheet in the source of supply, and means for withdrawing an insert from the second-named source of supply and inserting the withdrawn insert within the withdrawn portion of the folded sheet while at least a portion of the remaining portion thereof is held in the first-named source of supply.

17. An inserting machine having, in combination, a source of supply for folded sheets, a source of supply for inserts, means for withdrawing the first and a portion of the second leaves of a folded sheet from the first-named source of supply, means for holding at least a portion of the remaining portion of the folded sheet in the source of supply, means for withdrawing an insert from the second-named source of supply and inserting the withdrawn insert within the withdrawn portion of the folded sheet while at least a portion of the remaining portion thereof is held in the first-named source of supply, and means embracing the two vertical portions of the folded sheet withdrawn from the first-named source of supply for binding the insert within one of said portions and for completing the removal of the folded sheet from the first-named source of supply.

18. An inserting machine having, in combination, a source of supply for a plurality of 8 page folded sheets, means engaging the outermost face of a folded sheet in the source of supply, means engaging the second leaf of the folded sheet, and means for relatively operating said two means for withdrawing the first and at least a portion of the second leaves from the source of supply.

19. An inserting machine having, in combination, a source of supply for a plurality of 8 page folded sheets, a source of supply for inserts, means engaging the outermost face of a folded sheet in the source of supply, means engaging the second leaf of the folded sheet, means for relatively operating said two means for withdrawing the first and at least a portion of the second leaves from the source of supply to form a pocket between the first and second leaves, and means for withdrawing an insert from the source of supply thereof and inserting the withdrawn insert in the pocket formed between the first and second leaves.

20. An inserting machine having, in combination, a source of supply for a plurality of 8 page folded sheets, a source of supply for inserts, means engaging the outermost face of a folded sheet in the source of supply, means engaging the second leaf of the folded sheet, means for relatively operating said two means for withdrawing the first and at least a portion of the second leaves from the source of supply to form a pocket between the first and second leaves, means for withdrawing an insert from the second-named source of supply and inserting the withdrawn insert in the pocket formed between the first and second leaves, and means embracing the first and at least the portion of the fourth leaves withdrawn from the first-named source of supply for binding the insert within the first and second leaves and for completing the removal of the folded sheet from the first-named source of supply.

FRED W. BARKLEY.
